UNITED STATES PATENT OFFICE.

CECIL E. PAINE, OF BATH, MAINE.

HYDRAULIC STEERING-GEAR.

1,292,029.

Specification of Letters Patent. Patented Jan. 21, 1919.

Application filed November 17, 1918. Serial No. 131,908.

To all whom it may concern:

Be it known that I, CECIL E. PAINE, a citizen of the United States, and resident of Bath, Maine, have invented certain new and useful Improvements in Hydraulic Steering-Gears, of which the following is a specification.

My present invention relates to improvements in fluid operated mechanism for steering vessels and has for its primary object to provide a construction in which the necessary fluid under pressure may be supplied to the rams at will without the necessity of any reversible fluid compressor or pump and also without requiring the presence of any pressure storage tank or accumulator.

Other objects are to provide a steering gear or apparatus having various novel features of construction such as will hereinafter appear, and the invention includes the novel features of construction and arrangement and combination of parts hereinafter described and particularly defined by the appended claims.

An embodiment of my invention is illustrated in the accompanying drawings, in which,

Figure 1 is a plan view of such a steering apparatus, and,

Fig. 2 is a side elevation.

Fig. 3 is a diagrammatic detail view.

Figs. 4 and 5 are sectional detail views of the distributing valve.

Figs. 6 and 7 are sectional views of my preferred form of centrifugal pump and,

Figs. 8 and 9 are detail views of the detachable cross head nut.

Fig. 10 is a detail plan view of the tele-motor apparatus, and

Fig. 11 is a detail view of the connections for operating the valve by hand.

Referring by reference characters to this drawing the part designated by the numeral 22 is intended to be representative of the rudder post of a vessel, which post is provided with a rudder cross head 21. Links 19 and 20 connect the opposite ends of this cross head with suitable cross-heads 24 and 23 respectively, on the reciprocating members 17 and 18 of the hydraulic rams. These rams, four in number, comprise the opposed pairs of cylinders 14, 15, and 13, 16 respectively.

The member 18 has piston ends working in the first named pair of cylinders, and the

member 17 has piston ends working in the other pair of cylinders.

The movable members are designed to be operated simultaneously in reverse directions by the proper admission of fluid under pressure, (such for example as water) and its withdrawal or escape from the respective cylinders.

In order to secure a supply of fluid and distribute the same properly without requiring the use of either a reversing motor or pump, I provide one or more centrifugal pumps (two being shown in the accompanying drawing as a desirable arrangement) designated respectively as 3 and 4. The advantage of using two pumps is that when the ship is sailing on a straight course, or at reduced speed, less power is required to operate the rudder and hence one centrifugal pump may be put out of action, thereby saving the power necessary to operate it. These centrifugal pumps may be of the known or any desired construction and are designed to be driven continuously in one direction by suitable irreversible motors, of which the electric motors 1 and 2, shown conventionally in the drawings, are intended to be typical. When running idle, to wit, when the distributing valve is closed so that no fluid is being supplied to the rams to turn the rudder, the pumps run against pressure, so that fluid under pressure is always available when it is desired to admit the motive fluid to the rams to turn the rudder.

Centrifugal pumps operating against pressure, as when the distributing valve is closed, are likely to heat up, and to prevent them from overheating I provide them with water jackets having chambers or spaces 74 for cooling water and supply and discharge pipes 74^a and 74^b respectively, which may be supplied with water in any suitable manner.

Water is admitted to the pumps through supply pipe 40 which branches into 40^a leading to pump 3 and 40^b leading to pump 4. The discharge pipe from pump 3 is indicated at 5^a and from pump 4 at 5^b. These two pipes join and discharge into pipe 5 which is the pressure pipe and leads to the control valve 6. A connecting pipe 44 is shown which is to be used for a series of operations of cross connecting pipes 5^b and 40^a. The operation of the pump is as follows:

Both the supply pipe and the delivery pipe between the pumps are provided with branch pipes and cut off valves, indicated diagrammatically in Fig. 3, which valves 5 may be operated when one of the pumps is to be cut out.

Pump 3 when operating singly has the valves A and C open while the valves B and D are closed. Pump 4 operating singly 10 has valve D open while the valves A, B and C are closed. Pumps 3 and 4 operating in parallel have the valves, A, C and D open and the valve B closed. Pumps 3 and 4 operating in series have the valves A and 15 D closed, while the valves B and C are open.

The pipe connections between the distributing valve and ram cylinders are also provided with valve controlled branches as 20 shown in said Fig. 3, the purpose of which will hereinafter appear.

The valve casing of the distributing valve 6 is connected by a pipe 7 and connecting branches 8 and 9 to cylinders 13 and 14 and 25 by pipe 10 through connecting branches 11 and 12 to cylinders 15 and 16.

Branch pipes 8 and 9 are provided with cut-off valves E and F and branch pipes 11 and 12 are similarly provided with cut off valves G and H. Pipes 8 and 12 are 30 connected by a by-pass pipe controlled by a valve K and pipes 9 and 11 are connected by a similar by-pass pipe controlled by valve J.

When the distributing valve is set so that 35 the fluid flows through pipe 7 to cylinders 13 and 14, the cross head between cylinders 13 and 16 is forced outwardly and the cross head between cylinders 14 and 15 moved inwardly, imparting a corresponding movement to the rudder post. During this time the fluid in cylinders 15 and 16 escapes through branches 11 and 12 and pipe 10 to the discharge pipe 41.

When the distributing valve is shifted 45 so as to permit the fluid under pressure to flow through pipe 10 and branches 11 and 12 to cylinders 15 and 16, the reverse action takes place, the fluid escaping from cylinders 13 and 14 through the pipes which before served for conveying the pressure fluid.

The preferred form of distributing valve is shown in detail in Figs. 4 and 5.

Therein 55 is the valve spool which has a 55 lateral motion in either direction, traveling in bushings 56. Pressure from the pumps enters at passage 5 and passes out through passages 7 or 10 according to the lateral motion given the valve spool. In case the valve spool is moved to the left passage 5 is connected with passage 7 by the opening of port 60, allowing the liquid under pressure to pass through the pipes to their respective rams. At the same time the liquid which is 65 turned from the opposite rams through the

valve passages 10 and 41 would be connected by the valve spool opening port 61. A motion to the right of the valve spool connects passages 5 and 10 through opening of the port 61 and passages 7 and 41 by opening of 70 the port 60. Leak-offs are provided at either end as indicated at 59 and 59' which are to be connected to an exhaust line or tank, (not shown) equalizing the pressure and providing the means of escape for any 75 trapped liquid.

57 is the valve stem connected to valve spool 55, by means of a T slot milled in the valve spool and an engaging head on 57. Radial clearance is provided in the slot for 80 compensating errors of alignment. Motion is given stem 57 through lever 28.

The arrangement of the pipe connections between the rams and the control valves enables the cylinders to be worked in different 85 combinations as follows:

Four rams or cylinders in operation: The valves E, F, G and H are opened and valves J and K closed. Three rams in operation; the valves leading to operating cylinders 90 should be left open and valve to the inoperative cylinder, also valves J and K closed. Two rams in operation; i. e. 13 and 16, 13 and 15, 14 and 15, or 14 and 16 would have valves leading to the operative cylinders 95 open and valves to the inoperative cylinders and valves J and K closed.

For hand operation the pumps can be shut down; valves J and K to be left open. Whether the other valves are open or closed 100 is immaterial.

The distributing valve is controlled from a suitable telemotor of the ordinary or any desired construction such as the Brown telemotor which, being of well known construction, is shown in a partly diagrammatic manner, the pistons 31^a and 32^a of which, working in cylinders 31 and 32 actuate rocking lever 30, through the cross-heads 31^b and 32^b and the links or pitmen 31^c and 32^c. The lever 30 is supported by and secured to vertical shaft 30^a journaled in suitable fixed bearings 30^b carried by a suitable part of the ship's frame. One end of the rocking lever 30 is connected to a longitudinally elastic link 29, which in turn is connected to one end of floating lever 28 pivotally connected to the stem of the distributing valve. The other end of this lever is connected by a link 28^a to a rocking lever 12 27 centrally pivoted to a fixed support, and having its ends connected by links 29^a to the cross heads 23 and 24. When the distributing valve is shifted to admit fluid to cylinder 14, for example, and moves cross 12 head 23 to the right, lever 27 is rocked, moving link 28^a in the same direction, causing the distributing valve to be restored to neutral position and the rudder to be held in the position to which it has been moved 13

until the telemotor has been further operated.

The distributing valve is also capable of being operated mechanically from the hand wheel 34 through shafting 33 and 33^a and the bevel gear 33^b fast on shaft 33^a and meshing with bevel gear 33^c which is fast on shaft 30^a, and thereby is adapted to rock the lever 30.

10 Hand steering mechanism is also provided in the shape of one or more hand wheels 39 on shaft 39^a which is connected to screw shaft 38. This in turn is detachably engaged by cross head nut 36, and when said 15 nut is in engagement with the screw shaft operation of the steering wheels 39 imparts longitudinal travel to the nut, and through link 35 and rocking lever 25 pivotally connected to the cross head of member 18 and fulcrumed at 25^a imparts movement to link 20 and thereby to cross-head 21 and the rudder post 22.

The detachable connections for hand steering are shown in detail in Figs. 8 and 9 in which 38 is the hand gear screw, and 37 is a sleeve nut running on 38 and provided with a flange on one end flattened off on two opposite sides. 36 is the cross head nut which sleeve nut 37 fits into and on one face has a slot machined in which the flattened flange of 37 fits, which keeps 37 from turning when 38 is rotated. 45 is a retaining collar which is split to allow of assembling and has an internal shoulder which engages 5 with a shoulder on cross head nut, and a hole through its face and is in the shape of a round ended rectangle, which provides a lip at top and bottom, as shown. These lips engage with the flange on sleeve 37 and 10 lock it in place. By rotating collar 45 90° the nut can be backed out until clear of said collar 45 by rotating screw shaft 38, or the cross head 36 can be moved away from the nut until clear of collar 45. Then the nut 15 can be moved by hand back to its clear position where it is held by a spring actuated stop. Collar 45 is provided with a pin 46 actuated by a spring for keeping it either in a locked or free position. The cross head is guided top and bottom which prevents it from turning and at the same time takes care of any side thrust from links 35 allowing a free lateral motion. 47 is a guide bushing running on tops of threads of 38.

Having thus described my invention, what I claim is:—

1. In combination, a rudder post, a centrifugal pump connected with a source of fluid supply, a means for driving the same constantly in one direction, a double acting hydraulic ram operatively connected with said post, pipe connections from said pump to the respective cylinders of the ram, and a distributing valve adapted to admit fluid from said pump into either cylinder at will

and discharge it from the other cylinder, said valve in neutral position closing said pipe connections to the pump whereby the latter operates against pressure accumulated in said pipe connections.

70

2. In combination, a rudder post, a pair of centrifugal pumps, independent means for driving said pumps constantly in one direction, a double acting hydraulic ram operatively connected with said post, pipe 75 connections from said pumps to the respective cylinders of said ram, a distributing valve in said connections for controlling the admission of pressure fluid to and its discharge from said cylinders, and means for cutting one of the pumps out of action at will.

3. In combination, a centrifugal pump, means for driving the same constantly in one direction, a rudder post, a double acting 85 hydraulic ram operatively connected with said post, pipe connections from said pump to the respective cylinders of the ram, and a distributing valve adapted to admit fluid from said pump into either cylinder at will 90 and discharge it from the other cylinder, and telemotor apparatus for operating said valve.

4. In combination, a centrifugal pump, means for driving the same constantly in 95 one direction, a rudder post, a double acting hydraulic ram operatively connected with said post, pipe connections from said pump to the respective cylinders of the ram, and a distributing valve adapted to admit fluid 100 from said pump into either cylinder at will and discharge it from the other cylinder, telemotor apparatus for operating said valve, and mechanically controlled means for also operating said valve.

5. In combination, a rudder post and cross head, a pair of rams connected respectively to opposite ends of said cross head, a centrifugal pump, pipe connections from said pump to said rams, a distributing valve in 110 said connections controlling the admission of fluid to and its discharge from said rams, and means for operating said valve, comprising a rocking lever having its ends connected respectively to the moving elements 115 of said rams, a rocking lever fulcrumed on the stem of the distributing valve and having one end connected with one arm of said first named lever, and telemotor apparatus connected with the opposite end of said last 120 named lever.

6. In combination, a rudder post and cross head, a pair of rams connected respectively to opposite ends of said cross head, a centrifugal pump, pipe connections from said 125 pump to said rams, a distributing valve in said connections controlling the admission of fluid to and its discharge from said rams, and means for operating said valve, comprising a rocking lever having its ends con- 130

nected respectively to the moving elements of said rams, a rocking lever fulcrumed on the stem of the distributing valve and having one end connected with one arm of said first named lever, and telemotor apparatus connected with the opposite end of said last named lever, said connections including an elastic link.

7. In combination, a steering post having 10 a cross head, a pair of rams having their

moving parts linked to said cross head, means for admitting pressure fluid at will to either of said rams, a lever having one end fulcrumed to a fixed support, and its intermediate portion pivotally connected to 15 a moving part of one of the rams, and mechanically operated means for applying power to the opposite end of said lever.

In testimony whereof, I affix my signature.
CECIL E. PAINE.
